MOISTURE CONDITIONING TOBACCO CONTAINER

Perry W. Rodman, Bridgeport, Conn.

Application April 6, 1948, Serial No. 19,347

7 Claims. (Cl. 312—31.3)

1

The present invention relates to a moisture conditioning container for tobacco, either in the form of loose tobacco, cigars, or cigarettes, an object of the invention being to provide a container having a moisture conditioning chamber constituting a structural part of the container, namely, its base, as distinguished from moisture conditioning devices heretofore in use, which usually consisted of inserts or attachments for the container. These are unsatisfactory because they are not firmly fixed in the container, and interfere with the normal removal of the tobacco therefrom. They also make it difficult to renew the moisture conditioning medium and do not effectually condition the tobacco in a properly regulated uniform manner. The invention contemplates either a humidifying medium to add moisture to the tobacco, or a de-humidifying or dehydration medium to remove moisture therefrom.

It is particularly proposed according to the invention to provide a moisture conditioning chamber constituting the base of the container, including means for securing the side walls of the container thereto, thus making for an inexpensive, sturdy and attractive construction. It is a further object to provide a tobacco container having a moisture conditioning chamber constituting its base, and which also serves as a receptacle for dust particles from the tobacco contained in the container, so that these particles, which constitute an irritant when the tobacco is smoked, are effectually removed therefrom. A further object is to provide a tobacco container in which the humidifying or de-humidifying medium may be conveniently renewed without disturbing the contents of the container.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a side elevation of a tobacco container, according to the illustrated exemplary embodiment of the invention, portions of the same being broken away.

Fig. 2 is an end elevation.

Fig. 3 is a longitudinal sectional view, on an enlarged scale and partially broken away, taken along the line 3—3 of Fig. 2.

Fig. 4 is a horizontal sectional view, taken along the line 4—4 of Fig. 3.

Fig. 5 is a vertical sectional view, taken along the line 5—5 of Fig. 3.

2

Fig. 6 is a vertical sectional view, taken along the line 6—6 of Fig. 3.

Fig. 7 is a vertical sectional view, showing a modified form of the invention.

Fig. 8 is a vertical sectional view, showing another modified form of the invention.

Fig. 9 is a vertical sectional view, showing another modified form of the invention.

Referring to the drawings, the moisture conditioning tobacco container, according to the illustrated exemplary embodiment of the invention, comprises a container body consisting of flexible side walls 10 and 11, of leather, fabric, or the like, secured together at their ends by turned-in seams 12 and 13, and having secured along their upper edges a zipper fastener 14 of conventional type.

The lower end portions of the side walls 10 and 11 are secured within the moisture conditioning chamber which constitutes the base of the container, this chamber consisting of a longitudinally extending trough-like external member, indicated generally as 15, and comprising a rectangular base 16, longitudinal side walls 17 and 18 and end walls 19 and 20. The member 15 is constructed of pressed sheet metal, molded plastic, or other suitable material. Within the member 15 there is provided an internal base forming member, of inverted U-shape, indicated generally as 21, and comprising a longitudinally extending top wall 22 having perforations 23 therein and downwardly extending side walls 24 and 25, these side walls being spaced from the side walls 17 and 18 of the member 15 to provide spaces for receiving the lower end portions of the side walls 10 and 11 of the flexible container body.

These lower end portions are inserted between the side walls of the members 15 and 21, the fit between the parts being preferably such that the relatively flexible material of the walls 10 and 11 is tightly compressed to thus secure the parts together without any open seams or cracks in which particles of tobacco may lodge. The flexible walls 10 and 11 may be additionally secured by cement or other suitable adhesive. At its ends the upper wall 22 of the member 21 is notched out, as at 26 and 27, to receive the turned-in seam flanges of the members 10 and 11, so that the end portions of the flexible container body are firmly pressed against the end walls 19 and 20 of the member 15 by the ends of the top wall 22.

The end wall 19 of the member 15 is provided

with a threaded opening 28 in which is engaged a screw plug 29 to which there is secured a length of wick material 30, and which extends substantially the full length of the humidifying chamber. As illustrated the wick is secured to an inwardly projecting split stud portion 31 of the screw plug which is pressed into clamped relation with the wick. The wick is preferably twisted and engaged upon a stiffening rod or wire 32, also secured in the split stud portion 31, to position the wick centrally within the chamber out of direct contact with its walls and to facilitate its insertion and removal. The wick may be saturated with water, when used as a humidifying medium, or it may consist of suitable de-humidifying material, when used to remove moisture from the tobacco. Such material may be silica gel suitably applied to the wick, or the wick may be dispensed with and silica gel crystals inserted in the chamber, through the plugged opening 28. The arrangement of the wick within the chamber provides a substantial air space about the wick in which the evaporation or absorption of the moisture may take place and be absorbed by or abstracted from the tobacco within the pouch without direct contact of the tobacco with the wick. At the same time sufficient space is provided about the wick so that the moisture conditioning chamber may receive dust particles of the tobacco which may sift through the openings 23, so that these are effectually separated from the tobacco. Such particles may be readily removed through the opening 19 upon removal of the screw plug therefrom. It will be understood that the outline shape of the base and the forward material of the side walls may be changed, as desired, to accommodate the container of the invention to either loose tobacco, cigars, or cigarettes, as well as to pocket or table use.

In Fig. 7 there is illustrated a modified form of the invention, in which the inner base forming member, indicated generally as 21A, is provided in its side walls with shoulders 33—33 against which the lower ends of the flexible side walls of the container body are engaged, these lower ends being enclosed in reinforcing strips 34—34 bent about them. The upper edges of the side walls 17 and 18 of the member 15 are bent inwardly to form retaining flanges 35—35 so that the several parts are effectually locked together.

In Fig. 8 I have illustrated another modified form of the invention in which the inner base forming member, indicated generally as 21B, is formed of relatively stiff wire gauze bent into inverted U-shape.

In Fig. 9 I have illustrated another modified form of the invention in which the external chamber forming member 15C is provided in its side and end walls with downwardly extending pockets 36 in which the lower ends of the flexible side walls 10 and 11 are engaged and secured, either by being compressed therein or cemented, the turned-in seams being engaged in cut-outs 37 in the end walls. The inner base forming member 21C is formed of wire gauze, its side walls being inserted in the pockets 36. Notches similar to the notches 26 and 27 of the first embodiment are provided at the ends of the member 21C to receive the turned-in seams.

I have illustrated and described preferred and satisfactory embodiments of the invention but it will be understood that changes may be made therein, within the spirit and scope thereof, as defined in the appended claims.

What is claimed is:

1. A tobacco container, comprising a container body consisting of side walls, closure means at the upper side of said body, and chamber means constituting the base of said body and consisting of a base wall, upwardly extending side walls and end walls, and a moisture pervious top wall, there being downwardly extending pockets in said walls of said chamber means, the side walls of said body being engaged and secured in said pockets.

15 2. A container, comprising a container body consisting of side walls, closure means at the upper side of said body and chamber means constituting the base of said body and consisting of an outer chamber forming member having a base wall and upwardly extending side walls and end walls, an inner chamber forming member comprising a moisture pervious top wall and downwardly extending side walls inwardly opposed to the side walls of said outer member, the side walls of said body being engaged and secured between the side walls of said outer and inner members.

20 3. A tobacco container, comprising a container body consisting of side walls, closure means at the upper side of said body, and chamber means constituting the base of said body and consisting of an outer chamber forming member having a base wall and upwardly extending side walls and end walls, an inner chamber forming member comprising a top wall having perforations and downwardly extending side walls inwardly opposed to the side walls of said outer member, the side walls of said body being engaged and secured between the side walls of said outer and inner members.

25 4. A tobacco container, comprising a container body consisting of side walls, closure means at the upper side of said body and chamber means constituting the base of said pouch body and consisting of an outer chamber forming member having a base wall and upwardly extending side walls and end walls, an inner chamber forming member formed of wire gauze comprising a top wall and downwardly extending side walls inwardly opposed to the side walls of said outer member, the side walls of said pouch body being engaged and secured between the side walls of said outer and inner members.

30 5. A tobacco container, comprising a container body consisting of side walls, reinforcing members engaged about the lower marginal portions of said side walls, closure means at the upper side of said body, and chamber means constituting the base of said body and consisting of an outer chamber forming member having a base wall and upwardly extending side walls and end walls, an inner chamber forming member comprising a moisture pervious top wall and downwardly extending side walls inwardly opposed to the side walls of said outer member and having outwardly disposed abutment shoulders between their upper and lower edges, the reinforcing members of said side walls of said body being engaged and secured between the side walls of said outer and inner members in abutting relation to said abutment shoulders, the side walls of said outer member being bent inwardly at their upper edges above said reinforcing members.

35 6. A tobacco container comprising a container body consisting of side walls, closure means at the upper side of said body, and chamber means constituting the base of said body and consisting of a base wall, upwardly extending side walls and end walls, and a moisture pervious top wall, one

of the end walls having an aperture, a closure plug removably engaged in said aperture, a wick carried by said plug and engaged in said chamber means, and a stiffening member carried by said plug and extending longitudinally through said wick.

7. A tobacco container, comprising a container body consisting of flexible side walls secured together at their ends by turned-in seams, closure means at the upper side of said body, and chamber means constituting the base of said body and consisting of a base wall, upwardly extending side walls and end walls, and a moisture pervious top wall, there being downwardly extending pockets in said walls of said chamber means, the flexible side walls of said body being engaged and se- 10
15

cured in said pockets, and said top wall having notches at its ends engaged by the turned-in seams of said flexible side walls.
